UNITED STATES PATENT OFFICE.

FREDERICK M. WHYTE, OF TARRYTOWN, NEW YORK, ASSIGNOR TO HUTCHINS CAR ROOFING COMPANY, OF DETROIT, MICHIGAN, A CORPORATION OF MICHIGAN.

CAR-ROOF.

1,300,075.

Specification of Letters Patent.

Patented Apr. 8, 1919.

Application filed November 1, 1917. Serial No. 199,737.

To all whom it may concern:

Be it known that I, FREDERICK M. WHYTE, a citizen of the United States of America, residing at Tarrytown, in the county of 5 Westchester and State of New York, have invented certain new and useful Improvements in Car-Roofs, of which the following is a specification, reference being had therein to the accompanying drawings.

10 The invention relates to car roofs of the flexible type and has particular reference to the means for weather-proofing the eaves, permitting of ventilation. The construction may be applied to various specific forms 15 of roof, but is more particularly designed for use in connection with that type in which the roofing sheets are rigidly attached to the carlines, but are movable in relation to each other.

20 In the drawings, a portion of a roof to which my improvements are applied is shown in sectional perspective.

A are the carlines and B are the side- 25 plates which, as shown, are formed of an angle beam. The carlines are preferably of inverted channel-shaped section and may be attached to the side-plates by extending the end portions C over the outwardly-extending flange of the plate and secured by rivets 30 D. E are the roofing sheets which are rigidly secured to the carlines A by any suitable means, and extend outward over the outwardly-extending flange B' of the plate. The end portions of these sheets are return- 35 bent, as indicated at F, the inwardly-extending flange lying adjacent to the flange B' of the plate. H is a flashing strip, preferably extending continuously along the side of the car and having a returnbent portion 40 H' which embraces the inwardly-extending flange F of the sheet. This flashing strip is also preferably provided with a depend- 45 ing angle flange H², which extends downward beyond the edge of the flange B' of the side plate. The flashing strip is secured by suitable means, such as the angle clips I bolted or riveted to the flanges B' and H².

To weather-proof the joint between adjacent sheets, the latter are suitably flanged, 50 and the flanges are embraced by cap members J, which extend from eave to eave. The ends of these cap members are bent downward to form the depending flanges J'. K are strips of blocks upon the side- 55 plate B, having inclined upper faces form-

ing seats or bearings for the sheets, these being preferably formed of wood so as not to abrade the sheets in the relative movement of the same.

In assembling the roof, the flashing strips 60 H have their returnbent portions engaged with the returnbent portions F of the sheets before the latter are secured down, and subsequently said strips are themselves secured by the angle clips I. When in position, 65 the engagement of the returnbent flanges with each other will form a thoroughly weather-proof joint without interfering with freedom for relative movement of the sheets. It is, however, desirable to venti- 70 late the roof, permitting circulation of air without the introduction of moisture. To accomplish this, I have provided a series of apertures L in the returnbent portion F of the sheets through which the air can pass. 75 Any water which may enter through these apertures is prevented from finding access to the interior of the car by the returnbent flange H', and the apertures L are so located as to permit the water to drain out. 80 It will be understood that the air, after passing through the apertures L and past the flange H, can find access to the interior of the car through suitable openings, which may be formed in various ways. In the 85 present instance these openings are formed by spaces between adjacent blocks K.

What I claim as my invention is:

1. In a car roof, the combination with a side-plate, of roofing sheets extending over 90 said side-plate and having returnbent ends, a flashing strip having an opposite returnbent engaging the returnbends of said sheets and also provided with a depending outer flange, and ventilating apertures in the returnbends of said sheets.

2. In a car roof, the combination with a metallic side-plate having an outwardly-extending top flange, of carlines secured to 100 said side-plate, roofing sheets provided with returnbent outer ends above said flange, a flashing strip having an opposite returnbent portion engaging the returnbends of said sheets and provided with a downturned angle flange, and securing devices for said 105 flashing strip attached to said downturned flange and to the flange of said plate.

3. In a car roof, the combination with a metallic side-plate having an outwardly-extending top flange, of carlines secured to 110

said plate, roofing sheets supported on said carlines and having their outer ends returnbent above said flange, a flashing strip having an opposite returnbend therein engaging the returnbends of said roofing sheets and also provided with a downturned angle flange, and a series of clips or angle brackets secured to said downturned flange and to the flange of said plate to hold said flashing strip in position.

4. In a car roof, the combination with a metallic side-plate having an outwardly-extending top flange, of carlines connected to said plate, roofing sheets supported upon said carlines and having their outer ends returnbent above said flange, filler blocks resting upon said flange inside of said returnbends and forming a support for said sheets, a flashing strip oppositely returnbent and engaging the returnbends of said sheets, said strip being also provided with a downturned flange, and means for securing said flashing strip to said side-plate.

5. In a car roof, the combination with a metallic side-plate having an outwardly-extending top flange, of carlines secured to said side-plate, roofing sheets supported upon

said carlines and having returnbent ends above the flange of said side-plate, a series of ventilating apertures being provided along said returnbends, a flashing strip opposite the returnbend and engaging the returnbends of said sheets, said strip having a downturned flange, and means for securing said downturned flange to said side-plate.

6. In a car roof, the combination with a side-plate, of a supporting bearing on said side-plate extending above the same and having an angling upper face corresponding to the pitch of the roof, a roofing sheet supported on said bearing member and having an open returnbend beyond said supporting bearing above said plate, and a flashing strip secured to said plate having an opposite returnbend with an obliquely angling upper flange engaging the open returnbend of said sheet.

In testimony whereof I affix my signature in presence of two witnesses.

FREDERICK M. WHYTE.
